[57] **CLAIM**

The ornamental design for a “dual action walker”, as shown and described.

DESCRIPTION

FIG. 1 is a front elevational view of a dual action walker showing my new design;

FIG. 2 is a right side elevational view thereof, the left side being a mirror image thereof;

FIG. 3 is a top plan view thereof;

FIG. 4 is a rear elevational view thereof; and,

FIG. 5 is a bottom plan view thereof.
